UNITED STATES PATENT OFFICE.

CLIO B. YAW, OF ARLINGTON, NEW JERSEY, ASSIGNOR, BY MESNE ASSIGNMENTS, TO REMINGTON TYPEWRITER COMPANY, OF ILION, NEW YORK, A CORPORATION OF NEW YORK.

TYPE-WRITING AND ADDING MACHINE AND MEANS FOR AUTOMATICALLY OPERATING THE SAME.

1,124,378.

Specification of Letters Patent.

Patented Jan. 12, 1915.

Application filed June 21, 1911. Serial No. 634,475.

To all whom it may concern:

Be it known that I, Clío B. Yaw, citizen of the United States, and resident of Arlington, in the county of Hudson and State of New Jersey, have invented certain new and useful Improvements in Type-Writing and Adding Machines and Means for Automatically Operating the Same, of which the following is a specification.

10 My invention relates chiefly to mechanism for automatically operating a key-board instrument, said instrument in the present instance being a combined typewriting and adding machine.

15 The principal object of the invention is to provide a motor-driven machine for operating a combined typewriting and adding machine for display or exhibition or advertising purposes, to illustrate to the public

20 the mode of operation of the machine, and the results obtained by such operation. The invention, or parts of the invention, are applicable or adaptable, however, to the operation of other machines than the precise

25 one here illustrated, and some of the features of the invention are capable of application to machines that are not automatically operated.

My invention consists in certain features 30 of construction and combinations and arrangements of parts, all of which will be fully set forth herein and particularly pointed out in the claims.

One embodiment of my invention is illustrated in the accompanying drawings in which—

Figure 1 is a right-hand side elevation, with parts in section and parts broken away and parts omitted, of a combined typewriting and adding machine mounted on and connected with a machine for automatically operating said combined typewriting and adding machine. Fig. 2 is a front elevation of the same. Fig. 3 is a left-hand side elevation of part of the computing attachment and some of the associated mechanism. Fig. 4 is a fragmentary isometric view of a portion of a certain shifting device. Figs. 5 and 6 are fragmentary top views of de-

tails. Fig. 7 is a right-hand side elevation 50 of the operating machine with the typewriter mounted on it, said operating machine being shown in section a little inside of the right-hand frame-posts. This figure and Fig. 1 together constitute a right-hand 55 side elevation of the entire mechanism, partly in section. Fig. 8 is a view in horizontal section and looking downward, the section being taken on about the line $\alpha-\alpha$ of Fig. 7. Fig. 9 is a detail view. 60

I have illustrated my invention in connection with a Remington No. 11 typewriter having a Wahl adding machine mounted thereon. The main frame of said typewriter comprises a base 1, corner posts 2 65 and a top plate 3. Said top plate supports a pair of grooved rails 4 which, by means of balls or rollers 5, support a carriage 6 for travel back and forth across the machine. Said carriage is impelled toward 70 the left by a spring drum and strap, not shown. The step-by-step motion of said carriage is controlled by means including a feed rack 7 meshing with a pinion 8 which is connected with a pair of escapement 75 wheels 10, said escapement wheels being controlled by a dog pivoted on a dog rocker 11, which in turn is provided with a stationary pivot 12 and is operated by a link 13 connected with an arm 14 projecting from a 80 rock shaft 15 in the base 1 of the typewriter. Said rock shaft has at each end thereof an arm projecting toward the rear of the machine and supporting a link 16, which link supports a universal bar 17. Said universal bar lies beneath a series of printing key levers 18 which at their rear ends are pivoted on a flange 20 and which at their forward ends carry printing keys 21. Each of said key levers is connected by a link 22 85 with a lever 23 which is connected by a link 24 with a type bar 25 having one or more types 25^a on its free end. The series of type bars are pivoted on a segment 26 secured to the underside of the top plate 3, 90 and the type bars are arranged to strike upward and toward the rear against the front face of a roller platen 27, which is mounted

by its shaft 28 in the carriage 6. In the Remington machine said platen is mounted in a platen frame 30 which is adapted to be shifted up and down on links 31 for upper and lower case writing, this motion being limited by stop screws 32. As the present machine is intended only for writing numbers I have removed the mechanism for shifting the platen up and down and have 10 screwed the upper stop 32 down so as to hold the shaft 28 in its lower position. This, of course, is not necessary, however.

The right-hand end of the platen carries a line space wheel 33 which is adapted to be 15 engaged by a pawl 34 pivoted at 35 on an arm 36, the lower end of which is pivoted concentrically with the axle 28. The pawl 34 is operated by a link 37 which is pivoted to said pawl at 38 somewhat below the pivot 35. The forward end of the link 37 is pivoted to the vertical arm 40 of a bell-crank which has also a rearwardly extending arm 41, said bell-crank being pivoted at 42 to the carriage 6. The arm 41 is connected by 20 a link 43 with an arm 44 projecting from a horizontal rock shaft 45 which is journaled in a housing 46 on the carriage 6. The shaft 45 extends toward the front of the machine and its forward end is bent downward 25 forming a handle 47. In the Remington machine the pawl 34 normally stands in the dotted line position shown in Fig. 1; that is to say, the arm 36 is normally inclined toward the front of the machine and the 30 pawl stands out away from the wheel 33. When the handle 47 is pushed toward the right the link 43 is pushed downward and this link, through the lever 41, pushes rearward on the link 37. The first part of the 35 motion of said link turns the pawl 34 about its pivot 35 into engagement with the wheel 33 and the latter part of such motion moves the pawl and the arm 36 together, turning the ratchet wheel and the platen. In the 40 Remington machine the wheel 33 is formed with a uniform series of teeth each one of which corresponds to what is known in the typewriter art as a single space distance. For reasons which will appear hereinafter, 45 I have modified this wheel, making it with four series of four teeth each, each series consisting of three short or narrow teeth 50 and one wider tooth 51.

The Remington machine is provided at 50 the rear of the carriage with a paper table 52 suitably supported on the platen frame 30 and operating to support the loose part of the paper at the rear of the platen. Said machine is also provided with suitable feed 55 rolls and other paper feeding and guiding devices which are used in the present machine but which, being of ordinary and well-known construction, I have not thought it necessary to illustrate.

55 An ink ribbon 53 is mounted on ribbon

spools 54 which in turn are mounted on horizontal shafts 55 journaled in the framework of the machine. These ribbon spools are driven by the spring drum that moves the carriage but as the ribbon feed mechanism is of the ordinary construction, I have not illustrated it herein. The spools are disposed one on each side of the machine and the ribbon is guided from one to the other by means which include a ribbon vibrator 70 56 which, as indicated in Fig. 1, normally stands below the printing line but which is adapted to be thrown upward to cover the printing point at each actuation of a printing key. The means for thus operating the 75 vibrator includes a link 57 which at its lower end is connected with an arm 58 projecting from the rock shaft 15 of the universal bar 17 of the machine. I have not 80 illustrated the mechanism between this link and the vibrator but said mechanism is or may be like that fully shown and described in my Patent No. 920,410, dated May 4, 1909. Part of this intermediate mechanism is 85 mounted on a rail or cross bar 60 which in the regular Remington machine constitutes part of the platen shift mechanism. As I do not shift the platen in the present instance, I have removed this bar 60 from its usual supports and have secured it to the rear face of the type bar segment 90 26 in the same position that it would occupy in the ordinary machine when the platen is in the lower case position. It will of course be understood that this change 95 in the mechanism of the typewriter is not at all essential but has been made here solely for the purposes of simplicity and convenience.

The ink ribbon 53 is a bi-color ribbon 105 having an upper stripe *a* with black or blue ink and a lower stripe *b* preferably of red. The vibrator mechanism includes means for changing the extent of throw imparted to the vibrator 56 at each key stroke, a short 110 stroke being given to the vibrator to write in blue or black and a longer stroke to write in red. The mechanism whereby this change in the operation of the vibrator is brought about is fully set forth in my prior 115 patent above referred to. Said mechanism includes a rock shaft 61 (Figs. 1 and 2) which at its rear end is pivoted in a bracket 120 of the main frame and at its forward end is pivoted in a bracket 62 secured to the left-hand front post 2. The forward end of the shaft 61 has fixed thereon a milled head 63 and pointer 64, the latter co-operating with two indicating marks 65 and 66, the former colored blue or black and the latter colored red. 125 When the shaft 61 is turned so that the pointer 64 points to the mark 65, the ribbon mechanism is adjusted to write from the upper stripe of the ribbon. By turning the shaft till the pointer 64 registers with the 130

mark 66 the mechanism is set to write from the lower stripe of the ribbon.

The Wahl adding attachment includes an actuator 67 and a carriage 68 on which latter may be mounted one or more adding heads 70, one such adding head being here shown. Said actuator is suitably secured to the fore-part of the main frame of the typewriter and it includes a rock shaft 71 having rigidly mounted thereon a series of arms 72 set at various angles and each having a pin or a roller adapted to coöperate with a cam controlled by one of a series of levers 73. The several levers 73 are operated by links 74 which at their lower ends are connected with the key levers 18 of the numeral keys of the machine. When any of these numeral keys is depressed the shaft 71 is operated to an appropriate extent and it operates a master wheel, which in turn operates the register wheels 75 which show in Fig. 2 through a suitable slot in the front face of the adding head 70. All of this mechanism is well known in the art and I have not here shown it in detail. The mechanism includes, however, means for setting the machine so as to change the character of the arithmetical operations performed, said means in the Wahl machine being adapted to cause the number written on the typewriter to be either added or subtracted as desired. Said means includes a rod or bar 76, Figs. 2 and 3, which, when moved toward the right in Fig. 2, sets the machine for addition and when moved toward the left sets the machine for subtraction. In the ordinary use of the Wahl adding machine it is customary to add a column of figures and then to set this bar toward the left before writing the total, thus causing the total as it is written to be subtracted out of the adding machine, leaving the register wheels at zero. The carriage 68 is mounted in part on a stationary bar or bracket 77 which is supported by brackets 78 from the top plate 3 of the typewriter, said carriage being supported and guided by means which I have not here fully shown but which include certain rollers or wheels 80. The carriage 68 is also supported in part by arms 81 projecting one from each end thereof, said arms being connected by screw and slot connections 82 with arms 83 secured to the typewriter carriage 6.

The operating machine has a frame which comprises four corner posts 84 and a top 85 secured to said posts by bolts 86. The mechanism is situated beneath said top 85 and the typewriter is mounted on said top as shown in Figs. 1, 2 and 7. Said top is provided with short posts 87 which fit into the sockets ordinarily occupied by the rubber feet of the typewriter and thus locate the typewriter on said top. The typewriter is fastened to the operating machine by means

of bolts 88. The mechanism may be concealed by shields 90 of sheet metal, each extending from one of the posts 84 to another and each having a rod 91 secured thereto by ears or brackets 92 of the shields 90 and said rods at their ends being inserted in inclined slots 93 made in the sides of the posts or legs 84. With these shields in place the mechanism of the operating machine is concealed so that the typewriter and adding machine have merely the appearance of resting on a neat metal stand.

The machine is operated by a motor, here shown as an electric motor, 94 connected by wires 95 with any suitable source of power, such for example, as an ordinary electric light circuit. This motor is supported on a plate 96 which is secured by screws 97 to cross pieces 98 which in turn are suitably supported by two bars 100, one of which connects the two front legs and the other the two rear legs of the stand or frame. The shaft 101 of the motor has a worm 102 at one end, said worm operating a large worm wheel 103 which is mounted on the lower end of a vertical shaft 104 which at its upper end carries a bevel pinion 105. Said shaft 104 is journaled in a housing 106 secured to one of the cross bars 98, said housing being suitably elongated to provide a sufficiently long bearing for the shaft. The pinion 105 meshes with a bevel gear 107 mounted on a transverse horizontal shaft 108 which may not improperly be referred to as the main shaft of the machine. It will be seen that this main shaft is driven at a much lower speed than the motor shaft. The shaft 108 may be journaled in any suitable way but as here shown it is formed at its ends with recesses 109 and into each of the recesses there projects the rounded end 110 of a stud bolt 111 which passes through a bar 112 joining one of the front posts 84 with the corresponding rear post 84. Two nuts 113 are threaded onto the bolt 111, one of said nuts being outside and the other inside the bar 112. The bolts 111 can be adjusted by means of these nuts and secured rigidly in place by tightening them. Endwise motion of the shaft 108 is prevented by the ends of the bearings 110 contacting with the bottoms of the recesses 109.

The shaft 108 carries a series of cam disks or wheels which operate the various parts of the typewriter and adding machine. Beginning at the left-hand end of said shaft there is a cam wheel A which furnishes the power to operate the key levers 18 of the typewriter and controls the devices that operate said key levers. Next along the shaft comes the bevel gear 107 and next to that is a cam wheel B which operates the color controlling shaft 61 of the typewriter and the adding and subtracting

rod 76 of the adding machine. Following the wheel B are ten selector cam wheels C which control certain devices for selecting the particular numeral key lever 18 to be operated. The last cam wheel D effects the restoration of the typewriter carriage 6 to the right to begin a new line and the operation of the line spacing mechanism. These several cam wheels can be connected 10. to the shaft 108 in any suitable manner. As here shown said shaft is threaded throughout the greater part of its length and the cam wheels are spaced apart by a series of nuts 114 threaded onto the shaft and 15 clamped one after another against the several cam wheels. One of these nuts 115 at the left of the wheel 107 is shown in Fig. 8 partly rounded but with two flat faces for coöperation with a wrench. Each of the 20 numeral key levers 18 has pivoted thereto at 116 a depending link, coupler or connecting device 117 which is controlled in part by a contractile spring 118 connecting said link with the key lever 18 and tending 25 to swing the lower end of the link toward the rear of the machine. The links 117 pass down through a suitable opening or suitable openings in the top 85, and each of them terminates in contact with the front 30 edge of one of the cam wheels C.

As shown in Fig. 7 the lower end of each of the links 117 is made of peculiar form and for this reason it is convenient to make said lower end as a separate piece 120 secured to the main part of the link 117 by rivets 121. Said end 120 has a nose 122 that rests against the edge of the wheel C and said nose has an abrupt face 123 above and an inclined face 124 below. In order to 35 insure proper coöperation between the link and the wheel said link is provided with two ears or arms 125 which embrace the cam wheel to prevent lateral displacement of the link. The nose 122 is pressed against 40 the periphery of the wheel C by means of the spring 118. The part 120 is formed with a slot 126 opening upward and included between the main body of said part 120 and a branch 127 of said part. Each 45 of the wheels C has a circular periphery except that at intervals said disks are formed with notches 128 each having an inclined side 130. As the shaft 108 slowly revolves the noses 122 of the links 117 are all 50 held at a uniform distance from the axis of the shaft 108 until one of these notches 128 reaches one of said noses, when said nose drops into the notch, thus allowing the link to move a short distance toward the 55 rear of the machine. This rearward motion of the link brings the upper end of the branch 127 of that particular link directly beneath a reciprocating operating device, here shown as a bar 131 which extends 60 across the entire series of links and which is

mounted on the forward ends of two arms 132, which arms are rigidly mounted on a rock shaft 133 at the rear of the machine. The notches 128 are so disposed that no two of them lie in the same element of the 70 cylinder that includes the peripheries of the wheels C so that the links are brought into coöoperative relation with the bar 131 only one at a time. Means are provided for drawing said bar 131 downward each time 75 that any link 117 is allowed to drop back by reason of one of the notches 128. The downward motion of the bar 131 pulls down on the link 117 and operates the corresponding key lever 18 and the printing and adding mechanism connected with said key lever. The operation of said lever not only prints the number and adds it but also operates the universal bar 17 and the dog rocker 11 and allows the typewriter car 80 85 90 95 100 105 110 115 120 125 130 spring 145 and operates on whichever one of the branches 127 happens to be beneath said bar at the time. The downward motion of the operating frame is arrested by a 5 stop 143^a which is struck by the arm 143. In order to diminish or prevent the noise that such a blow might cause, I have constructed the stop 143^a of a block or post of wood, mounted at its lower end on one of 10 the cross-bars 98 and arranged to be struck on top by the arm 143. I have found this construction quite effective in reducing the noise. The adding head shown in the present case has six register wheels, and each of 15 the series of notches 134 is here shown as consisting of six of said notches, and four series of notches are provided. It will, of course, be understood that these numbers can be varied. The machine shown is 20 adapted to write and add three numbers of six digits each and then to write the total, and to subtract it out from the register after the ordinary fashion of the operation of the Wahl adding attachment.

25 The smooth parts 135 of the wheel A give time for the return of the typewriter carriage and the spacing of the paper to write a new line. The return of the typewriter carriage is effected by the wheel D, the outline of which is shown in Fig. 7. It will be seen that this wheel is formed with four inclined cam parts 148 each of which terminates in a high part or drop 149. The follower for this cam consists of a roller 150 mounted on a lever 151 pivoted at 152 to a bracket 153 depending from the top 85. As shown in Fig. 8 the lever 151 consists of two parallel pieces secured together in any suitable fashion at 154 and having the roller 150 between them. The lever 151 is acted upon by two springs 155 secured thereto at 156 and also suitably connected with the stationary framework. As here shown this connection comprises a threaded rod 157 with a hole that is hooked over a stationary pin 158. The construction is such that the tension on each of these springs can be regulated by loosening the rod 157 from the pin 158 and screwing it into or out of the 40 spring, the coils of which occupy the spaces between the thread of the rod. The free end of the lever 151 has pivoted thereto at 160 the lower end of a link or connecting rod 161 which is so constructed at 162 as to be adjustable to regulate its length. The rod 161 passes upward through the mechanism of the typewriting machine, as shown in Figs. 1 and 2, being pivoted at its upper end at 163 to the horizontal arm 164 of a bell crank which also has a vertical arm 165, said bell crank being pivoted at 166 to a bracket 167 secured as by screws 168, Fig. 1, to the top plate 3 of the typewriter. The 45 platen frame of the typewriter comprises a transverse horizontal bar 170, Figs. 1, 2 and 5, and the arm 165 lies just in front of this bar and just to the left of a pin 171 projecting forward from the bar. The construction is such that when the link 161 is pulled downward the arm 165 moves toward 70 the right against the pin 171, thus returning the typewriter carriage toward the right to begin a new line of writing.

In order to prevent accidental displacement of the arm 165, which would move it 75 out of coöperative relation with the pin 171, a guard plate 172 is secured to the front face of the bar 170, as shown in Fig. 5, this plate being so disposed as to leave between the plate and the bar 170 a slot 173 of such 80 length as to permit of the necessary relative motion between the arm 165 and the carriage. In Fig. 7 it will be noted that the follower 136 is on one of the smooth parts 135 of the wheel A and that the follower 85 150 has just dropped off of one of the high parts 149 of the wheel D. When said follower reaches the drop in this wheel the lever 151 is drawn down by the spring 155, thus operating the link 161 and lever 164, 90 165 and drawing the typewriting carriage back to begin a new line. The carriage will of course, be fed toward the left step-by-step as the follower 136 drops into the successive notches 134. This step-by-step motion is permitted by reason of the fact that the inclined part 148 of the wheel D, raises the lever 151 and moves the arm 165 toward the left faster than the typewriter carriage is moved toward the left, so that said arm 100 keeps out of the way of the pin 171 during the traverse of the carriage.

The Remington carriage is provided with margin stop mechanism, a part of which is shown in Fig. 6. Said mechanism includes 105 an adjustable margin stop 174 which co-operates with a stop 175 on the stationary framework. This stop 174 can be adjusted so as to positively arrest the carriage at the proper letter space position to begin the 110 writing of a new number. The machine is also equipped with a somewhat similar stop to limit the travel of the carriage toward the left and if desired, this stop may also be adjusted to a suitable position to come 115 into operation when the last digit of the added number has been written.

When the carriage is drawn back toward the right by the mechanism above described, it is necessary to rotate the platen 27 to a 120 suitable extent to space the paper for the next succeeding line of writing. This line spacing operation is effected automatically by the return motion of the carriage toward the right. A cam plate 176 is secured by 125 screws 177 to the top plate 3, said cam plate having its upper edge inclined as shown in Fig. 2. A lever arm 178 is secured to the bell crank 40, 41 of the line spacing mechanism, as for example by rivets 180. 130

This arm is adapted, when the carriage is drawn toward the right, to ride up the inclined upper edge of the plate 176 and thus to rock the lever arm 40 toward the rear of the machine, thus through the link 37, causing the pawl 34 to coöperate with the line space wheel 33 to turn the platen.

The present machine is arranged to write four numbers, that is to say, three numbers to be added and then the sum of those three numbers. It is desirable that said four numbers be line spaced uniformly and that the next succeeding line space be longer so as to separate the column of figures just written from the next column of figures. It is for this reason that the wheel 33 is formed with four groups of teeth, each group consisting of three teeth 50 spaced a suitable distance for the numbers of any given column and the fourth tooth 51 wider than the other so as to leave an additional space between the columns. In Fig. 1 the pawl 34 has just moved up one of the wide teeth. In this figure and in all the other figures the parts are shown in the position they occupy after having completed a column of figures, the mechanism being set to begin a new column. It will be noted that the dotted line position of the pawl 34 is low enough to engage one of the long teeth of the ratchet wheel but not low enough to catch the second one of two successive short teeth. The pawl thus feeds the ratchet wheel one tooth at each operation, the distance the platen is turned depending on the width of that particular tooth.

I have provided means for writing the items to be added in blue or black and the totals in red. I have also provided means for automatically setting the adding machine to add the said items and to subtract out the totals. These things being a part of the ordinary operation of the Wahl machine it is desirable to exhibit them in the present case. The change from add to subtract and vice versa and the change of color, are effected by the cam wheel B, the outline of which can be seen in Fig. 7. It will be noted that this wheel for about three-quarters of its periphery is circular in outline and that the remaining quarter is also circular but of less radius, the two parts being separated by inclines 181. This wheel controls a follower consisting of a roller 182 mounted on a lever arm 183 which is secured at 184 to the end of a rock shaft 185 and is journaled at its ends in the same brackets 186 that support the shaft 183. A spring 187 coiled about the shaft 185, is connected at one end to one of said brackets and at the other end to a collar 188 secured by a set screw 189 to the shaft 185. The tension of said spring is exerted to press the follower 182 against the wheel B and the tension of said spring can be regulated by loosening the set screw

189 and turning the collar on the shaft and then tightening the set screw. At its free end the lever arm 183 has pivoted thereto at 190 the lower end of a link or rod 191 that extends upward into the typewriter, 70 and at its upper end is pivoted at 192 to an arm 193 projecting toward the left from the rock shaft 61, the adjustment of which determines the color of the writing. When the follower 182 is on the high part of the 75 wheel B, the link 191 is held in its upper position and the machine is set to print in blue or black, and when the follower is on the low part of the wheel the link is pulled down by the spring 187 and sets the shaft 80 61 to print in red. The wheel B is adjusted on the shaft 108 so as to print the three items in blue or black and the total in red.

In order that the items may be added and the totals subtracted, connections are provided from the shaft 61 to the bar 76, the adjustment of which determines whether the adding machine is set for addition or subtraction. An arm 194 projects toward the right from the shaft 61 and said arm is connected with a link 195 which at its upper end is connected with an arm 196 of a plate-like lever 197 which is pivoted at 198 to the end plate of the actuator 67 of the adding machine. The plate 197 is formed with a 95 concentric slot 200 through which passes a screw 201 to hold said plate snugly against the end plate of the actuator and also to limit the extent of oscillation of said plate. As best shown in Fig. 4, the plate 197 has 100 formed on its upper end a flange 202 of cylindrical form, and in said flange is an inclined slot 203 having at one end a dwell 204 and at the other end a dwell 205. A pin 206 projects into this slot from the rod 76. The 105 construction is such that when the shaft 61 is set to print in blue or black, the upper part of the plate 197 occupies its rearmost position as shown in Fig. 3, so that the pin 206 is in the forward dwell 205 and the rod 110 76 is thus compelled to occupy its right-hand position, in which position the adding machine is set for addition. When the shaft 61 is rocked by a downward motion of the link 191, the link 195 is moved upward, forcing the plate 197 toward the front until the pin 206 occupies the dwell 205. This motion pulls the rod 76 toward the left and sets the 115 machine for subtraction.

In order to indicate whether the machine is set for addition or for subtraction and in order to call attention to the operation of the machine, I have mounted on the front of it an index 207 having a finger 208 that points to the sight-opening in the adding 120 head 70. In the Wahl machine this sight-opening and the numerals disclosed at it, are small and might, at least temporarily, escape observation unless attention was directed to them. The index 207 consists of a 125 130

sheet metal plate cut out in imitation of the shape of a human hand and with a part 210 that represents a man's cuff. This index is preferably of a color that contrasts with the 5 coloring of the machinery so as to attract attention. The index is preferably mounted on the adding machine carriage 68 by means of a post or posts 211, Fig. 3, projecting from said carriage toward the front of the 10 machine. In order to display the fact that the adding machine is sometimes adding and sometimes subtracting, an indicator 212 is provided having on it the words "Subtracts" and "Adds" these words being 15 adapted to show one at a time through a sight-opening 213 formed in the cuff part 210 of the indicator. Said indicator consists of a plate of sheet metal mounted on the back of the index 207 with freedom to slide 20 up and down. To this end said plate is formed with two vertical slots 214 through which pass headed screws 215 threaded into the index 207. The plate 212 extends a little below the plate 207 and is formed with a 25 rearwardly extending arm 216, Fig. 3, the bottom of which is elongated in a right and left direction as shown in Fig. 2. This elongated arm rests on an ear 217 bent off from an arm 218 which is secured to and 30 oscillates with the plate 197. The construction is such that when the parts are set for addition the word "Adds" shows through the sight-opening 213 and when the parts are set for subtraction the word "Subtracts" 35 shows through the same opening. I have imprinted on the index 207 the word "It" above, and the word "Here" below the opening 213, so that when the machine is adding the words "It adds here" are displayed. 40 and when the machine is subtracting the words "It subtracts here" are displayed. The elongated lower part of the arm 216 enables the said arm to slide back and forth with the motion of the adding machine carriage 45 without escaping from the arm 218. I prefer to mount another index bearing the legend "It prints here" and having its finger pointing at the writing line; this second index being merely fixed in any suitable way 50 to the typewriter carriage. As said second index does not involve any mechanical features of especial interest or novelty, it has not been shown in the drawing.

A machine of this character is best adapted for writing on a web of paper mounted on the machine in the form of a roll. I accordingly mount a roll of paper 220 on a drum 221 having a spindle 222 journaled at its ends in arms 223 secured to the base 55 part 1 of the typewriter frame by screws 224, the arms being curved rearward and upward and resting on the flat shelf at the back of the typewriter frame. The two arms 223 may be connected by one or 60 more rods 225 and provision may be 65 made in any suitable way for inserting a new roll of paper. For example, the arms 223 may be made of sheet metal and capable of being sprung apart to free the ends of the rod 222 to remove the old roll and 70 sprung over said rod again to insert a new roll. I have provided a sort of trough 226 which is secured to the paper table 52 by means of staples 227, the ends of which pass through holes in said paper table and are 75 secured in place by nuts 228. This trough as here shown has its right and left-hand edges bent up to form guides for the paper. This trough extends as shown in Fig. 1 80 backward to a point in the rear of the rear edge of the top plate 3. Said trough guides the paper accurately to the printing line and also prevents the paper from rubbing over the rear edge of the top plate. The paper is led from the roll upward to the 85 rear end of the trough 226, down through said trough beneath the staples 227 and around the platen and back again over the trough 226, the free end of the paper being allowed to fall down behind the machine. 90

In operation the motor is run continuously, thus giving a continuous motion to the shaft 108 and to the cam wheels mounted thereon. The several cam wheels are timed to act in harmony, that is to say, to 95 cause their respective followers to act at the right relative time to coöperate to produce the desired operation of the typewriter and computer. The notches 128 in the disks C are so disposed that one or another of the 100 noses 122 drops into one of said notches just before the follower 136 drops into one of the notches 134 in the wheel A. When said follower 136 drops into a notch 134 the bar 131 is drawn down by the spring 145 105 and said bar strikes on the top of the branch 127 of one of the links 117, depressing said link and operating the corresponding typewriter key. Near the bottom of the stroke of said link the inclined edge 124 of the nose 110 122 engages the incline 130 of the notch 128 and said nose is thereby cammed toward the front of the machine, moving the branch 127 out from under the bar 131 and releasing the key which is allowed to return immediately to normal position. In the interval between such release of the key and the next operation of the bar 131, the follower 136 rides up the inclined side of the notch 115 134, thus again elevating the bar 131. Meanwhile some other notch 128 reaches one of the noses 122 and the operation is repeated until one of the numbers has been written and added. Thereafter the follower 136 rides up on one of the 120 smooth parts 135 of the wheel A. The follower 150 drops off of one of the high points 149 of the wheel D and restores the carriage and line spaces the paper. These 125 operations are repeated until the three items 130

to be added have been written at the end of which time the follower 182 drops onto the low part of the wheel D and sets the machine for subtraction and for writing in red 5 and changes the indicator to show that the machine has been set for subtraction. The notches 128 are so disposed as to first write three numbers and then the correct total of said numbers. The problem and the answer 10 are thus worked out in the wheels C.

An electric motor geared so high with reference to the shaft 108 as it is here shown, will of course move said shaft with considerable power and in case of anything going 15 wrong with the mechanism the typewriting and adding mechanisms would be injured if said mechanisms were connected positively with the shaft. It will be noted that all of the typewriter parts are operated by springs 20 except that the shaft 61 is rocked positively in one direction. The keys are depressed by the spring 145 and the carriage is returned by the springs 155. By this construction if the parts became blocked in any 25 way there would be no more force applied to them than that due to the tension of said springs. Moreover, the keys are all actuated with the same degree of force, which can be regulated by adjusting the nut 147. 30 Moreover, the spring action gives a better operation to the key levers than a more positive action.

Various changes may be made without departing from the spirit and scope of my 35 invention.

What I claim as new and desire to secure by Letters Patent, is:—

1. In a machine of the class described, the combination with a series of finger keys, of 40 a series of selector wheels, one for each key, couplers connected to said keys and controlled by said selectors, a reciprocatory bar arranged to operate the selected coupler, a controller wheel for actuating said bar, and 45 means for moving said controller wheel and said selector wheels continuously in unison.

2. In a machine of the class described, the combination with a series of finger keys, of 50 links connected with said keys, a reciprocatory bar for operating said links, continuously movable selectors for normally holding said links out of the path of said bar and allowing said links to move into the path of said bar at predetermined intervals, 55 a controller for imparting reciprocatory motion to said bar, and means for moving said controller and said selectors continuously in unison.

3. In a machine of the class described, 60 the combination with a series of finger keys, of links connected with said keys, a series of selector wheels arranged to hold said links normally in inoperative position formed with means for allowing said links

to drop one at a time to operative position, 65 means for operating the link that is moved to operative position, and means for rotating said wheels.

4. In a machine of the class described, the combination of a key, a link connected 70 with said key, a bar for operating said link, a selector wheel for said link arranged normally to hold the link out of the path of said bar but having also one or more notches to allow said link to move into the path of said bar, and each of said notches arranged to cam said link out of the path of the bar at the end of an operation of said link, whereby the link and the key are left free to return to normal position independently of 75 the bar.

5. In a power operated machine for operating a key-board instrument, the combination with the keys of said instrument, of operating connections for said keys, a reciprocatory bar for operating said connections, 80 means for moving said connections one at a time into position to be operated by said bar, a spring for giving the operative stroke to said bar, and power operated means for 85 restoring said bar to normal position and putting said spring under tension.

6. In a power operated machine for operating a key-board instrument, the combination with the keys of said instrument, of 90 operating connections for said keys, a reciprocatory bar for operating said connections, means for moving said connections one at a time into position to be operated by said bar, a spring for giving the operative stroke 95 to said bar, and a power driven cam-wheel for restoring said bar to normal position 100 against the tension of said spring.

7. In a machine of the class described, the combination of a typewriting machine 105 having printing keys and a carriage, a series of selectors for said keys arranged to select said keys in a predetermined order, means for operating the selected keys, a controller for said operating means, means for returning the typewriter carriage to begin a new line, a controller for said carriage returning means, and means for moving said controllers and said selectors continuously in unison, said controllers and selectors being 110 timed to perform their several functions in proper sequence.

8. In a machine of the class described, the combination of a typewriting machine having printing keys and a carriage, of a 115 series of selectors for said keys arranged to select said keys in a predetermined order, means for operating the selected keys, a controller for said operating means, means for returning the typewriter carriage to begin a new line, a controller for said carriage returning means, and means for moving said controllers and said selectors continu- 120 125

ously in unison, said controllers and selectors being timed to perform their several functions in proper sequence, the first mentioned controller consisting of a wheel having a series of notches close together for operating the keys to write a line and a smooth part for holding the said key operating means stationary during the return of the carriage.

9. In a machine of the class described, the combination with a typewriting machine having printing keys and means for printing in different colors, of means for automatically operating the keys of said typewriter, means for changing the color of the printing to write a predetermined part of the written matter in a distinctive color, and a motor and connections for continuously moving said operating means and said color changing means in unison.

10. In a machine of the class described, the combination of typewriting mechanism including types and a traveling carriage, of a machine for automatically operating said typewriting mechanism, said machine having means for automatically operating said types in predetermined order, a cam wheel, a follower for said cam wheel, and a lever operated by said follower and adapted to return said carriage to begin a new line of writing, said lever and follower being controlled by a spring that returns the carriage and which is put under tension by said cam wheel.

11. In a machine of the class described, the combination with a typewriting machine having printing keys, a carriage and ribbon mechanism changeable to vary the color of the printing, of a machine for automatically operating said typewriting machine, said operating machine having a series of cams, certain of said cams being arranged to select the keys to be operated, means operated by another of said cams for operating the selected keys, means operated by another of said cams for returning the typewriter carriage, means operated by another of said cams for changing said ribbon mechanism, and means for driving said cams.

12. The combination with the types and carriage of a typewriting machine, of means for operating said types, said means including links, cam disks for controlling said links, each of said disks having notches therein into which a part of the associated link drops, means for operating any link that has dropped into one of said notches, said notches and links being so formed that when one of said links is operated it is cammed out of the notch and freed from said operating means.

13. The combination with the types and carriage of a typewriting machine, of a shaft having a series of disks or wheels

thereon, links connected with said types and 65 pressed against said wheels, a reciprocatory bar for operating said links, said links being normally held by said wheels out of the path of said bar and said wheels having notches to permit the links to drop into the 70 path of said bar and said notches formed to cam the links at the end of the operating strokes thereof out of the path of said bar whereby said links can return to normal position independently of said bar. 75

14. In a machine of the class described, the combination of a key-board instrument, a series of connecting devices for operating the keys of said instrument, a reciprocatory bar for operating said connecting devices, 80 means for moving said devices under said bar as required, a cam for operating said bar, a follower for said cam, an arm on which said follower is mounted, a second arm rigidly connected with said bar and 85 having two branches, and set screws in said branches for adjusting said first mentioned arm with relation to said rigidly connected arm.

15. The combination of printing instrumentalities, a series of connections for operating said printing instrumentalities, a reciprocatory bar for operating said connections, means for moving said connections selectively into position to be operated by 90 said bar, a spring for giving an operative stroke to said bar, and power operated means for restoring said bar to normal position and putting said spring under tension. 95

16. The combination with a typewriting 100 machine having keys, of an operating machine comprising means for operating certain of said keys in predetermined order over and over again, said means comprising a series of selectable connections each extending to one of said keys, a rotary cam shaft having a series of cams thereon for controlling said connections, and means for operating said connections. 105

17. The combination with a typewriting 110 machine having keys, printing instrumentalities and a carriage, of an operating machine for operating said keys, printing instrumentalities and carriage through a recurring cycle of operations, said operating 115 machine comprising a series of selectable connections appropriately extending to the recited parts of the typewriter, a rotary cam shaft having a series of cams thereon for controlling said connections, and means 120 for operating said connections. 120

18. The combination with a typewriting machine comprising as parts thereof a series of keys, a carriage, types and ribbon mechanism changeable to change the color 125 of the printing, of an operating machine for operating said parts through a recurring cycle of operations, said operating machine

comprising a series of selectable connectors appropriately extending to said typewriter parts, and a rotary cam shaft having a series of cams thereon for controlling said 5 connections.

Signed at the borough of Manhattan, city of New York, in the county of New York

and State of New York, this 20th day of June A. D. 1911.

CLIO B. YAW.
